UNITED STATES PATENT OFFICE.

SARAH G. HULL, OF OKLAHOMA, OKLAHOMA TERRITORY.

PERSPIRATION-POWDER.

SPECIFICATION forming part of Letters Patent No. 446,778, dated February 17, 1891.

Application filed November 18, 1890. Serial No. 371,833. (No specimens.)

To all whom it may concern:

Be it known that I, SARAH G. HULL, of Oklahoma, in the county of Oklahoma, Oklahoma Territory, have invented a new and Improved 5 Deodorizing Compound for the Body, of which the following is a full, clear, and exact description.

This compound or composition of matter has for its object the prevention of offensive odors 10 from certain or the more perspirable portions of the human body—such, for instance, as the armpits and feet.

The compound consists of burnt and pul- 15 verized alum and quinine, the latter acting as a tonic and the former as an astringent. Thus I take burnt and ground alum and sift it through a fine sieve, and to each half-pound of such prepared alum add about twenty grains (more or less) of quinine and thoroughly 20 mix the two ingredients together, when the compound is ready for use.

Such compound is applied externally. Thus it is applied to the flesh or parts to be treated and rubbed therein—as, for instance, to the 25 armpits and soles of the feet. A favorable time for applying it is after bathing or in the morning when making the toilet. It may also be used on the inside of the foot portions of

hose before putting the latter on, when the feet are to be treated with the compound to 30 destroy the disagreeable odor so conspicuously arising from these members with some people, and it will be found generally useful when applied to the other parts of the body, but ordinarily the armpits and feet to prevent effusive odors, great or small, from these parts. Its useful effect, however, will be more marked when applied to bad-smelling feet. 35

The compound is generally harmless and the application of it does not interfere with 40 free or healthy perspiration from the parts or members treated with it.

Having thus described my invention, what I claim as new, and desire to secure by Letters Patent, is—

The deodorizing composition for topical application to the human body, which consists of quinine and finely-pulverized burnt alum, in about the proportions of twenty grains of the former to eight ounces of the latter, substantially as specified. 45 50

SARAH G. HULL.
